UNITED STATES PATENT OFFICE.

WILLIAM D. ALLEN AND GUSTAVE A. JOHNSON, OF NEW HAVEN, CONNECTICUT, ASSIGNORS TO MARLIN FIRE ARMS COMPANY, OF NEW HAVEN, CONNECTICUT, A CORPORATION OF CONNECTICUT.

CUTTING-TOOL.

No. 857,710.

Specification of Letters Patent.

Patented June 25, 1907.

Application filed September 7, 1906. Serial No. 333,585.

To all whom it may concern:

Be it known that we, WILLIAM D. ALLEN and GUSTAVE A. JOHNSON, citizens of the United States, both residing at New Haven, New Haven county, Connecticut, have invented certain new and useful Improvements in Cutting-Tools, of which the following is a full, clear, and exact description.

Our invention relates to improvements in tools, and particularly for automatic taper cutting.

Our former patent No. 831,316, dated September 18, 1906 shows the principles of the machines with which our present invention is particularly intended for use. It is what is commonly known as an automatic cutting machine, in which the stock is a wire-like rod fed through the head of the machine. The cutting tools are carried usually by a turret rotatable on a vertical axis and movable longitudinally toward and from the stock. Other cutting tools are also sometimes provided, for instance, for cutting-off operations, which tools are moved transversely of the work axis.

Our former patent No. 834,877, dated November 6, 1906, illustrates a taper cutting tool embodying the principles of this invention. The improvements in this application reside principally in the means of connection between the cutter and saddle blocks and in a central abutment for steadyng the tip of the stock during the cutting operation.

Figure 1 is an end view of a tool embodying the improvements of our invention, Fig. 2 is a longitudinal section of the same taken on the plane of the line X—X, Fig. 1, looking up, showing a fragment of the end of the stock after the cutting operation. The outer line of the tool is also shown dotted in a position which it occupies as it moves to the position shown in full lines after the cutting operation. Fig. 3 is a bottom plan view of the tool, Fig. 4 is a detail view of one of the connecting links, Fig. 5 is a detail view of the other connecting link, Fig. 6 is a detail view of a bearing-block forming part of the connection between the links, Fig. 7 is a detail longitudinal sectional view of the central abutment for the stock.

The body 1 of the tool has a shank 2, which is adapted to be removably secured in the usual turret. The cutter-carrying block

3 and a saddle-carrying block 4 are mounted in guide-ways in the end of the tool in which they are adapted to slide toward and from the axis of the tool.

The cutter 5 and saddle 6 are suitably secured in the carrier blocks 3 and 4. The two carrier blocks are normally pressed outwardly by means of a suitable spring (not shown). Their outward movement is limited by adjustable screw stops 7 and 8. The carrier blocks are connected by levers 9 and 10 pivoted to the body of the tool by screws 11 and 12, respectively. A screw 13 passes through the double arm end 14 of the lever 9, and also through the bearing nut or block 15, which fits loosely in the notch 16 in lever 10. The screw 17 which takes into the cutter block 3 has its shank adapted to the notch 18 in link 9, while the screw 19 which takes into the saddle block 4 has its shank adapted to the notch 20 in lever 10. By means of this construction the two carrier blocks move in and out in their guide-ways simultaneously, and there is little opportunity for the parts to bind. The construction being simple, there is little likelihood of the parts being thrown out of adjustment or being clogged with dirt or chips from the work.

The stock 21 is fed through the head of the machine in the usual manner and the end given a tapering cut, as shown at 22, by means of the tool. In our former application, the saddle corresponding to saddle 6 is relied upon to steady the work during the cutting operation, but in some cases it is found desirable to give a further support to the stock. For this purpose, we have provided a central abutment, whose recessed end 23 receives a small tip 24 formed on the end of the stock. The body 25 of this abutment is guided in a longitudinal recess in the body of the tool and has a shank 26 guided in the sleeve 27, which is clamped in the shank of the tool by the screw 28. The spring 29 located between the body 25 of the abutment and the sleeve 27 holds the abutment in its proper position relative to the tool.

As the tool is moved toward the stock during the cutting operation, the abutment remains stationary and holds the tip of the stock rigid. When the tool is retracted, the

stock is released from the abutment after the tool passes to the right of the position shown in Fig. 2.

The advantages of this construction will 5 be apparent to those acquainted with this art.

What we claim is:

1. In a taper cutting tool, a body, radial guide-ways in said body at opposite sides of the center, a member mounted in each of said guide-ways, means to simultaneously move both of said members toward and from each other, a spring-pressed abutment mounted to slide in said passage normally engaging the inner faces of said members, and a smaller central projection therefrom extending flush with the outer faces of said members, said projection provided with a recess at its extremity to engage the stock.
2. In a taper cutting machine, a body and a shank, both provided with a central, longi-

tudinal passage, radial guide-ways in said body at opposite sides of the center, a member mounted in each of said guide-ways, means to simultaneously move both of said members toward and from each other, a spring-pressed abutment mounted to slide in said passage normally engaging the inner faces of said members, and a smaller central projection therefrom extending flush with the outer faces of said members, said projection provided with a recess at its extremity to engage the stock.

WILLIAM D. ALLEN.
G. A. JOHNSON.
